CHANDELIER

Betty Grace Page, 409 W. 59th St. Terrace,
Kansas City, Mo.

Filed Sept. 14, 1964, Ser. No. 81,704

Term of patent 14 years

(Cl. D48—3)

Fig. 1.

FIG. 1 is a perspective view of a chandelier embodying my new design.

FIG. 2 is a bottom plan view thereof.

The sides of the chandelier not shown are substantially the same as the side shown and the bulbs of the candle-like members are of an irregular flame-like shape.

I claim:

The ornamental design for a chandelier, as shown and described.
